BUS COWL

Filed May 4, 1927

2 Sheets-Sheet 2

UNITED STATES PATENT OFFICE.

ELBERT J. HALL, OF DETROIT, MICHIGAN, ASSIGNOR TO AMERICAN CAR AND FOUNDRY MOTORS COMPANY, OF NEW YORK, N. Y., A CORPORATION OF DELAWARE.

BUS COWL.

Application filed May 4, 1927. Serial No. 188,623.

This invention relates to motor buses and more particularly to an improved cowl and method of securing same all as hereinafter more particularly set forth.

5 An object of the invention is to provide a bus cowl or front end construction which may be quickly and readily assembled with the bus body frame and which will greatly increase the strength of this frame.

10 A further object of the invention resides in the provision of a cowl having integral upwardly extending portions perforated and adapted for attachment directly to a pressed channel-shaped corner post, one at each side 15 of the front end of the vehicle.

Other objects and advantages of this invention will be apparent from the following description when taken in conjunction with the accompanying drawings in which:

20 Figure 1 is a perspective of the front end of a motor bus constructed in accordance with my invention;

Fig. 2 is a vertical sectional view of the same;

25 Fig. 3 is a fragmentary horizontal sectional view taken on line 3—3 of Fig. 2;

Fig. 4 is a similar view taken on line 4—4 of Fig. 2;

Fig. 5 is a fragmentary plan view of the 30 bus roof frame;

Fig. 6 is a detail front elevation of one of the corner posts embodied in the invention, representing the right hand corner post as when in the vehicle and facing forwardly;

35 Fig. 7 is an enlarged fragmentary sectional view taken on the line 7—7 of Fig. 3, and

Fig. 8 is a fragmentary perspective view of one end of the rear edge of the cowl, showing 40 the attaching flanges.

Referring now more particularly to the drawings, in which similar characters of reference designate similar parts in the several views, a bus body frame is indicated generally by the reference character 5, this frame being provided with converging sill extensions 6 which extend forwardly from the wood side sills 6^a which are properly the body sills, and connected with the parts 5 and 6 are the corner posts 7 which posts are

formed from sheet metal pressed to the contour shown in the drawings and with recessed portions 7^a and 7^b provided, respectively, in the front faces and in the side faces of said posts 7 to accommodate the securing 55 flanges 8 and 9 which are cast integral with and adjacent the ends of the rear edge of the cowl 10, as clearly shown in Fig. 8. The flanges 8 and 9 serve as means for securing, by means of the screws 11, the cowl to the 60 posts 7, said screws extending through the metal of the posts and into the wood fillers 12, held within the posts 7 as best shown in Figs. 3 and 4. The flanges 8 and 9 preferably extend downwardly below the top surface 65 of the cowl, as illustrated in Fig. 2, and are connected to the posts 7 by fastening means identical with the parts 8, 9 and 11 before referred to.

The upper portion 10 of the cowl is preferably made in the form of an aluminum casting which will retain its shape and provide greater rigidity than the conventional sheet metal cowl, and this casting extends rearwardly as shown in the sectional view, 70 Fig. 7, the rear edge being formed into a channel portion 13 which opens upwardly and in which there is positioned a wood filler 14, which wood filler is held within the channel portion referred to by the screws 15 75 80 which secure the finishing strips 16 in position, said screws extending through the front flange of said channel portion, while machine screws 17 extend through the rear flanges of said channel portion and provide 85 means for fastening in proper position the cash register, fare box, change carrier or other element intended to be carried in convenient proximity to the driver of the vehicle. Lapping the forward flange of said 90 channel and being connected therewith by said screws just referred to is the metal 18 of the wind shield frame which, however, forms no part of the present invention, said frame resting, as shown in Fig. 7, upon the 95 wood filler before referred to.

The cowl casting is supplemented by the sheet metal dash 20 which is connected by the bolts or rivets 21 to the downwardly extending flange 22 of the cowl and serves 100

as a continuation thereof, said dash terminating at its lower end in the reinforcing corrugation 23 which extends from side to side entirely across the lower portion of said dash 20, while an inwardly extending angular flange 24 serves as the bottom portion of said dash. Said flange 24 receives and has connected with it braces 25, which, as shown in Figs. 1 and 2, are connected with 10 said flange 24 at one end and at their opposite ends are connected with the posts 7. Similar braces 26, 27 and 28 are formed integrally with the cast metal portion 10 of the cowl before referred to, said braces 15 being best shown in Fig. 2. Supplementing said braces and brace 25, serving as means for connecting the lower portion of skirt 10^a of the cowl with said posts 7, a pair of shelves 28^a are provided, one at each side. 20 These shelves are provided with flanges 29 which connect with the angles 30, which angles 30 serve to bind and reinforce the front edge portion of the cowl and serve as a stiffening member there- 25 for. The construction of the bus body rear- 30 wardly of the posts 7 forms no part of the present invention. Connected with the cast metal portion 10 of the cowl, sheet metal skirt portions 10^a are provided, as best shown 35 in Fig. 1, offset at 35 to form step-like por- 40 tions and the sheet metal skirt portion 10^a is connected to the angle 30 before referred to at its front edge and extends around the posts 7 and across the rear face thereof as 45 shown at 36 in Fig. 4. As this skirt por- 50 tion 10^a is of thin metal, preferably aluminum, it may be secured in position by the nails 37 which are driven through the sheets 10^a and into the wood post fillers 12, 55 thereby providing a substantial connection of said skirt portions of the cowl to the corner posts and thus materially strengthen- 60 ing the cowl structure. As is common in cowls of this type, a trap door, as 40, may 65 be provided at one or both sides of the cowl for ventilation.

It is believed that the construction and operation of the invention just described will be fully apparent to those skilled in 50 the art when the description is considered in connection with the accompanying drawings; however, it is not to be understood that the invention is restricted to the precise details shown in the drawings, as the latter 55 present only one embodiment of the invention, and obviously various changes in the form and proportions of the device may be made within the scope of the appended claims without departing from the spirit of 60 the invention.

What is claimed is:

1. A cowl for motor vehicles comprising a cast metal upper portion having a channel portion formed therein and having integral 65 vertically extending attaching flanges, and

sheet metal skirt portions connected with said upper portion.

2. A cowl for motor vehicles comprising a cast metal upper portion having integral attaching flanges on one edge thereof extending above and below said portion whereby to secure the upper portion to corner posts and sheet metal skirt portions connected with said upper portion and having extended rear ends for attachment to corner posts. 75

3. A cowl for motor vehicles comprising a cast metal upper portion having vertically arranged integral attaching flanges extending above and below the end of said portion, and sheet metal skirt portions connected 80 with said upper portion.

4. In a motor vehicle having channel corner posts and a nailing strip in each thereof, a cowl comprising a top portion, attaching means formed with said top portion and ex- 85 tending above and below the latter for securing the same to the corner posts, and skirt portions extending around the corner posts and secured to the rear thereof at the nailing strips. 90

5. In a motor vehicle having channel corner posts provided with a filler, a cowl comprising an upper portion having its inner edge terminating in an upwardly arranged channel, attaching means secured to the upper portion adjacent each end thereof for securing said upper portion to the corner posts, and skirt portions depending from said top portion and having their rear ends extended 95 around one side of each corner post and the 100 fillers therein.

6. In a motor vehicle, corner posts each having a recess in the front and one side thereof, a cowl comprising a cast metal top portion, vertically arranged attaching means 10 formed integral with the top portion adjacent each end thereof and secured to the corner posts in the recesses therein, and skirt portions having their rear ends extended 11 around the corner posts and secured to the rear thereof.

7. In a bus construction, a pair of channels each having a filler and forming corner posts, and a cowl having the top portion thereof secured to said channels and the skirt portions extended around the channels and secured to the fillers therein. 11

8. In combination with a vehicle body having corner posts, a cowl comprising a cast metal upper portion having attaching flanges adapted to extend adjacent the corner posts and to be secured thereto, and skirt portions connected with the upper portion and extending around the corner posts. 12

9. In a motor vehicle construction, corner posts having fillers, and a cowl comprising an upper portion having vertically arranged attaching flanges secured to the corner posts, and skirt portions connected to the upper 13

portion and extending around the corner posts and secured to said filler strips.

10. In a motor vehicle, a cowl comprising a single unit having a cast metal upper portion, attaching flanges formed integral with said upper portion and extending above and below the same for attachment to vehicle body posts, and skirt portions formed with the upper portion and having sides extending 10 around the body posts and secured thereto.

11. In a motor vehicle, pressed channels providing body posts, a filler in each body post, and a cowl having its side edges engaging at least two sides of said channels and 15 secured to the fillers, said cowl having at its rear upper edge vertically arranged attaching flanges angular in cross section engaging the channels and secured thereto.

12. In a motor vehicle, channel-shaped 20 corner posts, and a cowl provided adjacent the ends of the rear upper edge with vertically extending attaching flanges angular in cross section to engage the corner posts and to be secured thereto for supporting the 25 cowl.

13. In a motor vehicle, channel-shaped corner posts having a filler therein and a cowl having its rear upper edge provided with 30 vertically extending attaching flanges angular in cross section and engaging at least two sides of corner posts and secured thereto.

In witness whereof I have hereunto set my hand.

ELBERT J. HALL.
